UNITED STATES PATENT OFFICE.

ELMER M. SUMMERHAYS, OF HAMMOND, INDIANA, ASSIGNOR TO FREDERIC SCHAEFER, OF PITTSBURGH, PENNSYLVANIA.

METHOD OF MANUFACTURING CONNECTING PINS.

Application filed January 27, 1922. Serial No. 532,320.

To all whom it may concern:

Be it known that I, ELMER M. SUMMERHAYS, a citizen of the United States, and a resident of Hammond, in the county of Lake 5 and State of Indiana, have invented a new and useful Improvement in Methods of Manufacturing Connecting Pins, of which the following is a specification.

The invention relates to the manufacture 10 of pins having forged entering ends, and heads at their other ends, and particularly to the manufacture of connecting pins similarly characterized, now used in railway brake operating equipment. Such connecting pins are provided at the sides of their 15 entering ends with grooves connected to each other at their inner ends by holes extending through the body of the pins, in which holes and grooves there are placed 20 strips of bendable metal adapted to be turned outwardly to hold the pins in place.

In the manufacture of these pins two operations are required, one to forge the entering end of the pin, and the other to upset 25 its opposite end to form a head. This is objectionable not only because of the manufacturing cost involved in the two operations, but also in the case of the connecting pins because their upset heads 30 contain more metal than is required to make them of a strength commensurate with the holding power of the strip of bendable metal at the other end.

The object of this invention is to provide 35 a method of manufacturing headed pins having forged ends in general, and in particular headed connecting pins having grooves formed at their entering ends, whereby the heads of the pins may be 40 formed simultaneously with the forging of the other ends and the heads reduced in size, with the result that the cost of manufacture may be materially reduced.

The invention may be best explained with 45 reference to the accompanying drawings, Fig. 1 is a side view of a connecting pin of the character explained above; Fig. 2 an end view of the head of the pin; Fig. 3 a 50 longitudinal sectional view of the pair of forging dies used in the manufacture of the

pin; and Fig. 4 a plan view of one of the dies in Fig. 3.

In the practice of the invention in its applicability to the manufacture of pins of the type illustrated in Fig. 1, a head is formed 55 at the end of a pin by means of the same dies that are used for forging the grooves and hole in the entering end of the pin. A cylindrical blank of proper length is heated and placed between a pair of dies formed 60 at one end for forging the grooves and hole in the entering end of the pin, and formed at their other end to spread the opposite end of the blank laterally to form an elongate head overhanging the body of the pin. 65

As shown in Figs. 3 and 4 the forging dies may comprise similar members 1 and 1^a, each provided with a ridge 2 to form a groove on the side of the pin and with a projection 3 to form a hole through the body 70 of the pin connecting the inner ends of the grooves to each other. At the other end of the die members the head of elongate shape is formed in the die portions 4 by spreading 75 the metal laterally.

As shown in Figs. 1 and 2 the pin thus formed comprises a cylindrical body portion 5, side grooves 6 at its entering end having a hole 7 connecting the inner ends 80 of the grooves to each other, and a head 8. The head being of elongate form and overhanging the body 5 of the pin only at its ends, contains much less metal than the round heads heretofore formed by upsetting the ends of the pins. The pin is much more economical to manufacture than those heretofore produced, both because of the smaller amount of metal used and of the elimination 85 of the head-forming operation as a step in addition to the forging of the entering end. In finished form the pin is provided with a strip 9 of bendable metal which extends through the hole 7 and lies in the grooves 6 so that the pin may be readily 90 inserted through the holes in members it is intended to connect.

I claim:

1. The method of forming a cylindrical blank and in a single operation a headed pin 100 having a forged entering end, which com-

prises spreading laterally, by the same dies used for forging the entering end of the pin, the other end of the blank to form an elongate head overhanging the body of the 5 pin.

2. The method of forming from a heated cylindrical blank and in a single operation a headed connecting pin having a forged groove at its entering end, which comprises 10 spreading laterally, by the same dies used

for forging the grooves in the entering end of the pin, the other end of the blank to form an elongate head having its ends overhanging the body of the pin.

In testimony whereof, I sign my name.

ELMER M. SUMMERHAYS.
